UNITED STATES PATENT OFFICE.

EDWARD R. IVES, OF BRIDGEPORT, CONNECTICUT.

DESIGN FOR A TOY-HOLDER FOR FIRE-WORKS.

Specification forming part of Design No. **11,537**, dated December 9, 1879; application filed August 21, 1879.
[Term of patent 7 years.]

To all whom it may concern:

Be it known that I, EDWARD R. IVES, of Bridgeport, in the county of Fairfield and State of Connecticut, have invented a new and original Design for a Toy, of which the following is a specification.

Certain toys for using combustible compounds known as "Pharaoh's serpents' eggs," so that they will protrude from the toys as they burn, have been used.

My invention relates to such toys; and it consists in a design for a toy representing a human figure, such as that of a boy, with the head thrown forward of the body, and with the mouth open.

The accompanying drawing represents a perspective view of a toy embodying my invention.

The toy is intended to be made of metal or other suitable material. It is made in the form of a boy shown in a stooping posture, with the head thrown forward of the body, holding one hand to his abdomen, and the

other, with a cigar between the fingers, to his breast, an expression of sickness being alike portrayed by his face.

What I claim as my invention, and desire to secure by Letters Patent, is—

1. The design for a toy for holding Pharaoh's serpents' eggs while burning, consisting in the representation of a human figure with the head thrown forward of the body, and the mouth open, as in vomiting, as shown in the accompanying illustration.

2. The design for a toy for holding Pharaoh's serpents' eggs while burning, consisting of the representation of a boy in a stooping posture, holding one hand to his abdomen, and the other, with a cigar between the fingers, to his breast, the mouth being open, and the face expressive of sickness, substantially as shown in the accompanying drawing.

EDWARD R. IVES.
